MOUNTING FOR PLURAL GLASSWARE
FORMING NECK PINS AND THIMBLESWalter K. Berthold, Rockville, Conn., assignor to
Hartford-Empire Company, Hartford, Conn., a
corporation of Delaware

Application February 17, 1941, Serial No. 379,275

7 Claims. (Cl. 49—76)

The invention relates generally to the manufacture of glassware and more particularly to the neck pin and thimble mechanism of a glassware forming machine.

An object of the invention is to provide a simple, reliable and efficient mechanism for mounting and operatively supporting a plurality of adjacent neck pins or plungers and their thimbles suitably for simultaneous or concurrent use of these elements in the formation of the neck portions of a plurality of articles of glassware.

A further object of the invention is to provide a mounting for a plurality of neck pins and their thimbles so constructed and arranged that the pins are capable of horizontal floating movements relative to their thimbles during the assembly of several neck pins and their respective thimbles and thereafter each neck pin and its thimble may have a horizontal floating movement as a unit relative to their supporting structure and to each other neck pin and thimble unit.

A further object of the invention is to provide a mechanism of the character described which will afford facilities for supplying air under pressure from a common source to the several neck pin and thimble units of the mechanism, as for counterblowing the glass parisons which have been partially formed by the use of these units.

Other objects and advantages of the invention hereinafter will be pointed out or will become apparent from the following description of a practical embodiment of the invention, as shown in the accompanying drawing, in which:

Figure 1 is a fragmentary vertical section, taken substantially along the line 1—1 of Fig. 3, showing a pair of neck pins and their thimbles and a mounting therefor in accordance with the present invention;

Fig. 2 is a view similar to Fig. 1 but at a plane at a right angle therewith, the section being taken substantially along the line 2—2 of Fig. 3; and

Fig. 3 is a partial plan and partial section of the structure shown in the preceding views, the section being substantially along the line indicated at 3—3 of Fig. 1.

A mechanism embodying the present invention, as shown in the drawing, includes a pair of neck pins 10 and their thimbles 11. As best seen in Fig. 1, each neck pin 10 has a relatively enlarged substantially cylindrical base portion 10a provided with a flat bottom surface resting upon the flat upper surface of a laterally extending wing portion 12 of the head 13 of a rod-like vertical carrier 14. The rod-like vertical carrier 14 may comprise a plurality of aligned sections, detach-

ably coupled together. This is for convenience in assembling the mechanism. As shown, the upper section of the rod-like vertical carrier 14, with which the head 13 is integral or by which such head is directly supported, is connected by a coupling 15 of the split ring type with a lower section 16.

The thimbles 11 have out-turned flanges 11a at their lower ends resting upon circular shoulders 17 at the upper ends of circular openings 18 in the oppositely disposed wing portions 19 of a substantially horizontal plate-like member 20. The member 20 is carried by a vertically movable tubular carrier 21, being secured rigidly thereon, as by cap screws as indicated at 22 in Fig. 2. The vertical carrier 21, like the carrier 14 may comprise a plurality of aligned vertical sections. As shown, carrier 21 has an upper section on which the plate 20 is directly supported and a vertically aligned cylindrical lower section 22 connected with the upper section by a coupling 23 of the split ring type. The carrier for the thimbles serves as an upright cylindrical guide for the carrier for the neck pins. As shown, the carrier for the neck pins has a portion of the section 16 thereof slightly enlarged peripherally, as at 16a, to fit closely, although slidably, in a portion indicated at 22a of the section 22 of the carrier for the thimbles. These portions of the two carriers may be provided with a means for preventing leakage of air between them, as by providing piston rings 24 on the portion 16a of the inner carrier. The outer carrier also serves to retain the parts of the split coupling ring 15 in place during relative vertical movements between these carriers.

The outer carrier is mounted for vertical reciprocation in a casing which may comprise a substantially cylindrical lower section 25 and a hollow upper or head section 26, secured detachably to the lower section 25, as by a bayonet joint 27 and a retaining nut 28. The cylindrical lower section 25 of this casing may have a portion thereof reduced in diameter, as at 29, Figs. 1 and 2, to provide a close sliding fit with the lower section 22 of the carrier for the thimbles. The casing 25—26 may rest in a suitably apertured frame structure, a portion of which is shown at 30. This outer casing also serves to retain the sections of the split coupling 23 in place.

The casing 25—26 may be provided at its upper end with a top plate 31, secured in place by cap screws 32, and provided with openings at 33 through which the thimbles 11 extend.

The structural features of the invention which

permit the floating movements of the neck pins and thimbles previously mentioned will now be pointed out. The wing portions 12 of the head of the vertical carrier for the neck pins are provided with vertical openings 34. Each of these openings 34 is in substantially axial alignment with one of the openings 18 in the plate 20 and with one of the openings 33 in the casing top plate 31. A stud 35 has its body portion located in one of the openings 34 when the threaded upper end portion 35a of this stud has been screwed into a threaded axial opening 36 in the lower or base portion of one of the neck pins. When such neck pin and the opening 34 are axially aligned, the body of the stud 35 is spaced from the wall of the opening 34 by an annular space of appreciable radial extent, as indicated at 37 in Figs. 1 and 3. A concavo-convex spring washer 38 may be placed on a reduced lower end portion 35b of the stud and pressed at its peripheral edge against the bottom surface of the head 13 by a nut 39 on the lower end portion of the stud. The spring action of the washer 38 may serve to hold the base of the neck pin against the upper surface of the head 13 firmly but yieldingly in that the neck pin may be shifted or "float" horizontally on the head of its carrier under lateral pressure. This may serve two purposes as presently will be explained.

The thimble 11 associated with each neck pin has its bore enlarged from its lower end upward for part of its height, as at 40, Fig. 1, so as to have a close sliding fit with the relatively enlarged base portion 10a of the neck pin. The flanged lower end 11a of the thimble has a diameter appreciably smaller than that of a counterbore 41 that is formed in the plate 20 at the upper end of each opening 18. An annular space 42 thus is provided around the flanged lower end of each thimble when the latter rests upon one of the shoulders 17 in axial alignment with an underlying opening 18 in the plate 20, all as shown in Fig. 1.

A retaining plate 43 overlies the plate 20 and is provided with a pair of similar openings 44, each of less diameter than the flanged lower end of the associate thimble 11 but of greater diameter than the underlying opening 18. These openings 44 afford horizontal clearance for the thimbles 11 when the edge portions of the plate around such openings overlie the flanged lower ends of the thimbles and prevent vertical movement thereof relative to the plate 20. The retaining plate 43 is secured to the plate 20, as by cap screws indicated at 45 in Fig. 2. The arrangement is such that each thimble is retained firmly in place on its carrier but, under lateral pressure, may have limited lateral or horizontal floating movements relative to its carrier. The openings 33 in the casing top member 31 are sufficiently larger than the thimbles to permit such lateral floating movements.

The provisions above described permit each neck pin to move slightly in any horizontal direction relative to its carrier. This movement may be relative to its thimble 11 during the assembly of a neck pin on its carrier and a thimble on its carrier. Thereafter, the close sliding fit of the lower or base portion of the neck pin with the internally enlarged lower portion of the thimble will prevent relative horizontal movements between these parts but both may float horizontally as a unit relative to their carriers.

These capabilities of relative horizontal movements between the neck pin and its thimble dur-

ing assembly and between each neck pin and its thimble as a unit and the other neck pin and thimble as a unit permit these glassware neck forming elements to be accurately aligned with the glass receiving and forming cavities of each of a plurality of generally similar glass parison molds with which such neck pins and their thimbles may be used at different times, even though slight differences may exist between the several parison molds as to the distance between the vertical axes of their cavities. Also, the several neck pin and thimble units will be self-adjusting as to their horizontal spacing to be properly aligned with twin cavities of the same parison mold with which such units are used even if wear on the mold parts or on their supporting structures would otherwise impair such alignment.

The carrier for the neck pins may be provided with a central bore 46. This bore is closed at its upper end by a portion of the head 13 but communicates through lateral passages 47 in the wing portions 12 of such head with the spaces 37 which surround the studs 35 by which the neck pins are secured to the head 13. These spaces 37 are closed at their bottoms by the aforesaid spring washers 38 but are in open communication at their upper ends with radial passages 48 in the lower portion of the neck pin. These radial passages 48 in turn communicate with upwardly extending passages 49 which open through the outer wall of the neck pin at the juncture of the relatively enlarged lower portion thereof with its upper portion, as shown in Fig. 1. In practice, air under pressure for use in a glass forming operation, as to counterblow the glass in the cooperative cavity of the aforesaid parison mold may be supplied through the bore 46 to the neck pins and thence through the space between each neck pin and its thimble into and through the bore of the latter into the neck portion of the glass in the associate parison mold. This counterblowing operation may be timed to take place after or on downward retraction of the neck pins.

The carrier for the neck pins may be moved vertically at the times and to the extent desired when the device is in use. For the purpose of effecting such movements of this carrier, any suitable mechanism may be employed. However, I prefer to use an operating mechanism such as that disclosed in Fig. 15 of a patent to H. W. Ingle, 1,911,119 of March 23, 1933, for effecting vertical movements of the vertical member 165 of the structure there shown. Also, any suitable known mechanism may be employed for effecting desired vertical movements of the carrier for the thimbles but I prefer to use for this purpose a structure substantially like that shown in Fig. 15 of the aforesaid Ingle Patent 1,911,119, for effecting vertical reciprocation, of the member 139 of the structure therein shown. The carriers for the neck pins and thimbles, respectively, may be moved in unison or the carrier for the neck pins may be moved downwardly in advance of the carrier for the thimbles. The carrier for the thimbles may be moved upwardly from downwardly retracted position in advance of the carrier for the neck pins, if desired.

The invention is not limited to the exact details shown in the drawing and herein described as various changes therein and modifications thereof may be made by those skilled in the art.

I claim:

1. In a mechanism for mounting and mov-

ably supporting a plurality of neck pins and a like number of thimbles for cooperating with said neck pins, a vertically movable carrier for said neck pins, means for fastening said neck pins to said carrier to move in unison therewith and to permit limited lateral movement under pressure of each neck pin relative to said carrier, a second vertically movable carrier for said thimbles, and means for fastening said thimbles to said second named carrier to dispose each thimble in adjacent cooperative relation with a neck pin and to cause said thimbles to move vertically with the second named carrier and to permit limited lateral movement of each thimble under pressure relative to the second named carrier.

2. A mechanism for mounting and movably supporting a plurality of glassware neck forming units, each comprising a neck pin and a cooperative thimble surrounding the neck pin, vertically movable supporting means for said units, and means for connecting said units with said vertically movable supporting means to move vertically in unison therewith and to have limited independent lateral movements under pressure relative to each other and to said supporting means.

3. A mechanism for mounting and movably supporting a plurality of glassware neck forming units, each comprising a neck pin and a cooperative thimble, comprising a vertically movable carrier for the neck pins, means for securing the neck pins in place on said carrier to move in unison therewith, a vertically movable carrier for the thimbles, and means for securing the thimbles in place on said second named carrier so that each thimble surrounds a neck pin, said first named carrier having a passage for receiving fluid under pressure from a source of supply and branch passages communicating with spaces between the associate cooperative neck pins and thimbles for supplying thereto fluid under pressure from said first named passage.

4. In a mechanism of the character described, a plurality of neck pins, a vertically movable carrier comprising an upright elongate body and a head at the upper end thereof, said head having laterally extending portions respectively provided with vertical openings corresponding in number with said neck pins, studs fastened to said neck pins and extending through said openings in spaced relation with the walls thereof, and means engaging said studs beneath said head to restrain said neck pins against upward displacement from said head and to permit limited lateral movements of the neck pins relative to the head.

5. In a mechanism of the character described, a plurality of neck pins, a vertically movable carrier comprising an upright elongate body and a head at the upper end thereof, said head having laterally extending portions respectively provided with vertical openings corresponding in number with said neck pins, studs fastened to said neck pins and extending through said openings in spaced relation with the walls thereof, means engaging said studs beneath said head to prevent upward displacement of neck pins

from said head and to permit limited lateral movements of the neck pins relative to the head, a thimble surrounding each neck pin, said thimbles having externally flanged lower end portions, a plate located above the head of said carrier, said plate having openings beneath each thimble loosely accommodating the lower end portion of the neck pins and having counterbores above said openings for supporting the flanged lower end portions of the thimbles, the peripheries of said flanged portions being spaced from the walls of the counterbores, a retaining plate secured on said first named plate and having openings loosely accommodating the bodies of the thimbles and of less diameter than the flanges at the lower ends of the thimbles, the edge portions of the retaining plate around said openings overlying the flanged lower end portions of the thimbles, and vertically movable means surrounding the body of said first named carrier for movably supporting said plates and said thimbles.

6. In a mechanism of the character described, a plurality of glassware neck forming units, each comprising a neck pin and a cooperative thimble, vertically movable means carrying said neck pins and said thimbles, and means for connecting said neck pins and said thimbles with said vertically movable means so constructed and arranged as to permit limited relative horizontal movement between each neck pin and its thimble during the assembly of these members to form a unit as aforesaid and thereafter to permit limited relative horizontal movements between the several neck pin and thimble units.

7. In a mechanism of the character described, a plurality of neck pins, a vertically movable carrier for all of said neck pins, said carrier comprising an upright rod-like member having a substantially flat head including wing portions extending laterally of said rod-like member, said wing portions having vertical openings therein corresponding in number with said neck pins, said neck pins having attaching studs depending through said vertical openings and of sufficiently less diameter than said openings to provide annular spaces of substantial extent between the respective studs and the surrounding walls of said openings when the studs are centered in such openings, said neck pins being of greater diameter than said vertical openings at the ends of said neck pins next to said wing portions, concavo-convex spring washers on said studs beneath said wing portions with the concave surfaces of said washers turned toward such wing portions, and means engaged with the lower end portions of said studs beneath said washers to press the washers into firm contact at their edges with the under surfaces of said wing portions and thereby to pull said neck pins into contact at their lower ends with said wing portions firmly so that said neck pins will be moved vertically with said carrier during vertical movements of the latter and the individual neck pins may have independent limited lateral movements relative to said carrier in response to lateral pressures on said neck pins.

WALTER K. BERTHOLD.
